SAFETY LAMP GUARD

Michael Vincent Di Sapiro, Brooklyn, N. Y., assignor to Alexander Joseph Heidt, Woodhaven, N. Y.

Application October 2, 1940, Serial No. 359,415

1 Claim. (Cl. 240—102)

The present invention relates to portable lamp guards of the type made almost entirely of insulating material, and particularly to an improved construction by which a hook of the same material is secured to the cage which surrounds the lamp bulb.

In prior devices of this character, one form of which is shown in the Wilson Patent No. 1,958,222, dated May 8, 1934, the guard is made up of a plurality of cage forming elements of insulating material, one end of each of which is secured to a disk, to which the hook, also of insulating material, is attached. In the patent, the hook is held in position by locking nuts engaging the threaded base of the hook and holding a shoulder on the hook against the disk, thereby, to a slight degree, limiting the turning of the hook with respect to the cage.

Safety lamp guards of this character are subject to extremely rough use, and the hook, after a period of time, frequently becomes weakened at the shoulder near the base and breaks at this point. The principal object of the present invention is to provide for a reenforcement of the shank of the hook so that the above objection may be avoided.

After a period of use, the hook on a guard of this character frequently becomes so freely turnable with reference to the guard that the hook no longer remains in the desired position. My invention overcomes this difficulty by a connection which frictionally holds the hook against undue swiveling movement, so that said hook will not work loose after a period of use.

Other and further objects and advantages of the present invention will more fully appear from the following description, taken in connection with the accompanying drawing, in which—

Fig. 1 is a side elevation of a safety guard embodying the invention.

Fig. 2 is a fragmentary sectional view showing the connection of the hook to the rest of the guard.

Fig. 3 is a sectional view along the line 3—3 of Fig. 2.

Fig. 4 is a sectional view along the line 4—4 of Fig. 2.

Like reference characters refer to like parts in the different figures.

With reference to the drawing, the guard is intended to shield a light bulb 1 in a socket, not shown, in the end of a handle 2. The guard is releasably secured to the handle in any suitable manner, as by a resilient ring 3, this structure

being fully described in the above Wilson Patent No. 1,958,222.

The cage or guard is made up of a plurality of strips 4 of insulating material with one end of each strip held between a pair of disks 5 and 6, to which a hook 7 is also secured. The strips 4 are preferably riveted to the disks, as by rivets 8, and the strips are also attached between their ends to a peripheral annular strip 9 which holds the strips 4 away from the light bulb. The ends of the strips 4 remote from the disk 5 are held beneath the ring 3, as shown.

In accordance with the present invention, which, as above stated, involves a reenforcement 15 of the shank of the hook, and also a new type of connection between the disks 5 and 6 and the hook, the shank 1a of the hook has a threaded bore 10 therein to receive an elongated machine screw or bolt 11 having a head 12. The machine screw passes through a metallic washer 13, through the disk 5 and upwardly through the base 1b of the hook and into the shank 1a. The machine screw thus forms a rigid metallic re-enforcement to prevent breakage of the hook at a 20 point adjacent to its connection to the disk 5.

The upper disk 5 has a centrally located opening 14 to receive the base 1b of the hook. The latter, which is normally rectangular in cross-section, has its base 1b formed by cutting away a 25 part of the edges of the hook to define a substantially cylindrical portion fitting within the opening 14. The formation of the base portion 1b of the hook defines shoulders 1c on the hook. These shoulders are held securely against the 30 upper face of the disk 5 by the clamping action of the machine screw 12 and washer 13 as the screw is tightened within the shank of the hook. A locking pin 15 may extend laterally through the shank of the hook and the machine screw 35 to lock the parts in position after assembly.

In assembling the device the upper disk 5 is positioned on the base 1b of the hook and the machine screw 12 and washer 13 are then placed in position and tightened to hold the disk securely 40 against the shoulders 1c to assure a frictional engagement between the hook and disk to hold said hook against undue swivelling movement with respect to the disk. The strips 4 and bottom disk 6 are then placed in position and secured together and to the disk 5 by the rivets 8, there being a central opening 16 in the disk 6 to receive the head of the machine screw 12. This opening 45 16 is preferably so dimensioned that the edges thereof will engage the head of the screw 12 securely enough to materially increase the fric-

tional resistance which prevents undue swivelling of the hook with respect to the rest of the guard.

I claim:

In a lamp guard, a non-metallic non-conducting hook having a shank, a disk to which the shank of the hook is secured, said hook having a shoulder engaging with the side surface of the disk, a metallic clamping screw extending through said disk and into the hook to make rigid the

connection therebetween and to reinforce the shank of the hook, a washer between the head of the screw and said disk, a pin extending laterally through the hook and screw for locking the latter in position, a second disk substantially concentric to said first disk and having an opening therein engageable with the head of the screw, and cage elements having the ends thereof positioned between and secured to said disks.

10 MICHAEL VINCENT DI SAPIO.
